UNITED STATES PATENT OFFICE.

BARTON J. PARKER, OF HOUSTON, TEXAS.

TROWEL.

1,332,232.

Specification of Letters Patent. Patented Mar. 2, 1920.

Application filed October 2, 1917. Serial No. 194,329.

To all whom it may concern:

Be it known that I, BARTON J. PARKER, a citizen of the United States, residing at Houston, in the county of Harris and State 5 of Texas, have invented certain new and useful Improvements in Trowels, of which the following is a specification.

This invention relates to new and useful improvements in a trowel.

10 The object of the invention is to provide a trowel of the character described which is specially designed for applying plastic material in the formation of structures formed of concrete or other similar material and 15 having hollow walls. The trowel may also be used in the formation of wainscoting and finishing and in fact wherever it is necessary to apply plastic material in the construction of a wall, vessel or other structure.

20 Another feature resides in the provision of an implement whereby the plastic material may be applied in a smooth and uniform layer to the lathing, studding or other framework.

25 A further feature of the invention resides in the provision of a trowel to which the plastic material, to be applied, is delivered by means of controllable fluid pressure.

30 A still further feature resides in the provision of a trowel which is specially designed for use in the construction of boats and water craft formed of concrete or other similar material and having curved walls or sides.

35 With the above and other objects in view, the invention has particular relation to certain novel features of construction, operation and use, an example of which is given in this specification and illustrated in the 40 accompanying drawings, wherein:—

Figure 1 is a side elevation of the complete device.

Fig. 2 is an edge view thereof.

Fig. 3 is a transverse sectional view taken 45 on the line 3—3 of Fig. 5.

Fig. 4 is a top plan view of the trowel proper.

Fig. 5 is a fragmentary transverse sectional view of the device.

50 Fig. 6 is a fragmentary sectional view thereof, taken on the line 6—6 of Fig. 5.

Fig. 7 is a side view of a modified form of the trowel designed to be used in constructing curved walls.

Fig. 8 is an edge view of said modified 55 form, and

Figs. 9 and 10 are fragmentary vertical sectional views thereof.

Referring now more particularly to the drawings wherein like numerals of reference designate similar parts in each of the figures, the numeral 1 designates a container provided with a covering 2 and fixed in the upper part of which is a hopper 3 which is provided to receive a quantity of plastic 60 material. The hopper has an outwardly flared discharge opening which is controlled by a correspondingly flared valve 4. This valve is pivoted to the inner end of a lever 5 which in turn is pivoted to the bail 6 by 65 means of which the container is supported. The remainder of the container has an up-standing arm 7 whose upper end 8 is bent over and receives the set screw 9 which is threaded therethrough. When the outer 70 end of the lever 5 is engaged under said screw, the valve 4 is held tightly closed. When it is desired to open the valve, the outer end of said lever may be disengaged and elevated, which will operate to lower 75 80 the valve and permit the discharge of the plastic material from the hopper 3 down into the container 1. The container is provided with an agitator 9 of any desired form which may be manipulated through 85 the crank 10, so as to overcome the tendency of the material to "set" while in the container. The numeral 11 refers to the trowel which is formed of the required dimensions to fit between the studding 12, 12, and the 90 lathing 13, 13, of the wall framework and is held spaced a uniform distance from said studding and lathing by means of outwardly projecting fins 14 and 15. The upper part 95 16 of the trowel is reduced and tapers to an apex and fitted thereover but spaced therefrom is the hood 17 which is fixed relative to the trowel by means of the oppositely disposed transverse bridges 18, 18, which are soldered or otherwise secured to 100 the sloping edges of the trowel and to the sides of the hood 17. The upper ends 19, 19, of these bridges are left free and are upwardly turned, thus spacing said free ends apart. The upper part of the hood is formed 105 into a neck 20 to which the casing of the valve 21 is secured. A conduit 22 leads from the container 1 and is controlled by said

valve 21 and discharges the plastic material from said container through the hood 17. The stem of the valve 21 has an operating lever 23 fixed thereon to the free ends of 5 which are attached operating cables 24, 24, through which the valve may be opened and closed by means of the operating lever 25 to which said cables are attached.

In building a vertical wall, the trowel is 10 let down between the studding 12 and lathing 13 to the bottom of the wall, as shown in Figs. 1 and 2, the entire device being suspended by means of a block and tackle, not shown, or by any other suitable method.

15 The container is filled with the material to be applied, and when the valve 21 is opened, this material is forced by air pressure, admitted into the container through the pipe 26, through the hood 17 and is forced down 20 through the spaces between the sides and ends of the trowel and the lathing 13 and studding 12 to the lower end of the trowel. The material passing down through the neck 20 is separated by the upwardly turned 25 ends 19, 19, and a part of it diverted toward each end of the trowel and the remainder thereof passes between said upwardly turned ends and is separated by the apex of the trowel passing on each side of 30 the trowel so that a uniform quantity of material will be delivered to the ends and sides of the trowel and the upwardly turned ends 19 are left free so that they may be forced toward each other or spread apart, 35 as desired so as to regulate the quantity of material to be delivered to the ends and sides respectively, of the trowel. While the material is being delivered, the trowel is gradually elevated and as it moves upwardly to 40 the top of the wall, it is held spaced from the studding and lathing by the fins 14 and 15 and a sufficient quantity is delivered so that it will entirely fill the space 45 between the trowel and the studding and lathing and will be forced through the reticulated studding and lathing and may then be smoothed by the ordinary hand trowel applied to the outside of the wall, thus forming a smooth outer finish as 50 so that when the wall is completed the studding and lathing will be completely incased in plastic material, which when it hardens will form a monolithic structure.

In order to prevent the clogging of the 55 material in the conduit 22, I have provided fluid pressure conduits 28 and 29 which lead from the pipe 26, are controlled by the re-

spective valves 30 and 31, and enter the conduit a short distance above the hood 17.

It is obvious that this trowel may also 60 be used for forming floors and ceiling and other horizontal walls but when so used, the conduit 22 will preferably be formed of a flexible hose or pipe and the container 1 swung from a stationary support. 65

This form of trowel is also specially adapted for use in the construction of boats and water craft built of concrete and other similar material. Inasmuch however as the walls of water craft are curved, the trowel 70 11' has been formed of sections jointed together, as shown in Figs. 9 and 10 to permit a certain amount of flexibility so that in applying the material, the trowel will readily follow the curved contour of the 75 wall, as shown in Fig. 8.

What I claim is:

1. A device for applying mortar to the curved walls of ships and the like comprising an elongated flexible trowel, said trowel being 80 formed of sections hinged together having substantially flat parallel side faces, a conduit communicating with the exterior of said sections through which plastic material is delivered into the path of said sections 85 and means on both side faces of said sections for spacing said sections from the walls being plastered.

2. A trowel formed of a body portion said body portion formed of jointed normally 90 alined sections, said sections being capable of being flexed in the direction of their length from said alined position to accommodate said trowel to the curvature of spaced curved walls. 95

3. A trowel having substantially flat parallel side faces, said trowel adapted to be inserted within a hollow wall, means on both of said side faces for spacing the trowel from the inner face of the wall, and a conduit 100 communicating with the exterior of said trowel through which plastic material is delivered to the space between said wall and said side faces, said trowel being flexible throughout its entire length to accommodate 105 said trowel to the curvature of spaced curved walls.

In testimony whereof I have signed my name to this specification in the presence of two subscribing witnesses.

BARTON J. PARKER.
